UNITED STATES PATENT OFFICE.

WALTER GRAY, OF FORT HUACHUCA, ARIZONA, ASSIGNOR OF ONE-HALF TO EUGENE P. FRIERSON, OF FORT HUACHUCA, ARIZONA.

AUTOMATIC TRAIN-STOP.

1,277,063.

Specification of Letters Patent. Patented Aug. 27, 1918.

Application filed October 2, 1915. Serial No. 53,845.

To all whom it may concern:

Be it known that I, WALTER GRAY, a citizen of the United States, residing at Fort Huachuca, in the county Cochise and State 5 of Arizona, have invented certain new and useful Improvements in Automatic Train-Stops; and I do hereby declare the following to be a full, clear, and exact description of the invention, such as will enable others 10 skilled in the art to which it appertains to make and use the same.

This invention relates to automatic train stops, and has for its primary object to provide a novel and efficient mechanism designed 15 to open the train pipe of the air brake system and thus apply the brakes and automatically stop the train and operable by the operating mechanism of a block or other signal.

20 A further object of the invention is to provide an improved means operated by an electric motor carried by the locomotive for automatically opening the train pipe, when the circuit of the motor is closed, so as to 25 automatically set the brakes of the locomotive and thus bring the same to a stop.

With this and other objects in view, the invention consists in the novel construction, arrangement and formation of parts as will 30 be hereinafter specifically described, claimed and illustrated in the accompanying drawings, in which:

Figure 1 represents a fragmental side elevation of a railroad track and engine illustrating the improved train pipe opening device applied to use thereon,

Fig. 2 represents a front elevation of the electric motor and co-acting parts for automatically stopping the train.

40 Fig. 3 represents a side elevation of the mechanism illustrated in Fig. 3.

Referring to the drawing in detail, wherein similar reference numerals designate corresponding parts throughout the several 45 views, the numeral 10 indicates a suitable support provided at any suitable point upon a locomotive and upon which is supported a cylinder 12, having connection at its lower extremity with the train pipe 11 of the air 50 brake system of the locomotive. A cap 13 is fitted over the upper open end of the cylinder 12 and is formed with an opening constituting an air outlet port and which is beveled so as to provide a seat for an inwardly opening valve 14. A stem 15 is con-

nected with the valve 14 and is rigidly secured at its upper extremity to the lower edge of a vertically movable member 16. At the end opposite the stem 15, the plate 16 is rigidly secured to a rod 17, which latter is 60 extended through the upper extremity of a spring holder or cylinder 19 and is provided with a piston 18 slidably mounted within said holder and normally retained in upwardly extended position by the tension of 65 a coil spring 20 disposed within the cylinder or holder between the piston 18 and the support 10. The plate 16 is formed centrally with a depending rod 21 slidably mounted through an aperture formed in the 70 support 10. A coil spring 22 is coiled about the rod 21 between the support 10 and the vertically movable member 16 and is designed to assist the spring 20 in normally retaining the vertically movable member in 75 upwardly extended position so as to retain the valve 14 in closed position.

The vertically movable member 16 is provided with oppositely inclined surfaces 23 adapted to be engaged by a crank pin 24 80 carried by a disk 25, which latter is rigidly secured to the shaft 26 of an electric motor 27. The motor 27 is suitably supported in position above the vertically movable member 16 upon a support 27a.

85 Signal towers or standards 28 are arranged at the desired points along the railroad 28a in the upper extremities of which are pivoted signal arms 29. These arms are adapted to automatically close the circuit to 90 the contact rails 36, positioned adjacent the rails of the track 28a, when the arms are thrown into danger signaling position.

The locomotive 10 is provided, preferably at a point adjacent the forward end thereof, 95 with depending conductor cylinders 38a arranged for engaging the contact rails 36. When the electrical circuit to the motor 27 is closed, the latter is set in operation, thus moving the crank pin 24 into engagement 100 with the bevel or inclined face 23 of the vertically movable member 16, moving the latter downwardly against the tension of the springs 20 and 22 and simultaneously opening the valve 14, which latter permits the 105 air to exhaust from the train pipe 11 and effects an application of the brakes, thus stopping the train.

What I claim is:

In an automatic train stop, a train pipe, a 110

cylinder communicating with said train pipe, a valve arranged in said cylinder, a stem carried by said valve projecting exteriorly of the cylinder, a vertically movable member connected with said stem and having an inclined upper face, a second cylinder arranged in spaced parallel relation to the first-mentioned cylinder, a rod carried by the vertically movable member extending 10 downwardly within the second-mentioned cylinder, means associated with said rod normally retaining the vertically movable member in elevated position, means arranged

between said stem and said rod normally tending to elevate said vertically movable member, a motor, and a crank pin connected with said motor adapted to engage the inclined face of said vertically movable member to depress the latter and open said valve.

In testimony whereof I affix my signature 20 in presence of two witnesses.

WALTER GRAY.
